PULLEY HOUSING FOR A TRAVERSE ROD ASSEMBLY

James A. Ford, Sturgis, Mich., assignor to Kirsh Company, Sturgis, Mich., a corporation of Michigan

Filed Jan. 7, 1963, Ser. No. 73,071

Term of patent 14 years

(Cl. D21—1)

FIGURE 1 is a front perspective view of a pulley housing for a traverse rod assembly embodying my new design;

FIGURE 2 is a rear elevational view thereof;

FIGURE 3 is a top plan view thereof;

FIGURE 4 is a bottom view thereof;

FIGURE 5 is an end elevational view of one end thereof; and

FIGURE 6 is an end elevational view of the other end thereof.

The broken line showings of the traverse rod in FIGURE 1 and the pulley assembly in FIGURES 5 and 6 are for illustrative purposes only.

I claim:

The ornamental design for a pulley housing for a traverse rod assembly, as shown and described.
